HARLOW H. HATHAWAY, OF LOS ANGELES, CALIFORNIA

BUILDING CONSTRUCTION

Application filed September 15, 1928. Serial No. 306,137.

My invention relates to building constructions, and more particularly to lathing whereby a great bonding or clinching power is provided for a plastic material, after it has set, which material may be applied in the usual manner, either by hand or a pressure gun, as in practice desired.

As is well known, when the conventional wooden lath is used in building constructions, either on the inside or the outside of the building, it is necessary to soak the laths thoroughly with water to swell the same, so that after the plastic material is applied the lath will not swell and break the clincher and a more thorough clinching or bonding action is attained when said material sets and the lath dries.

If this manner is not applied the plastic material usually results in the cracking of the set material, or even the dropping thereof, especially after a hard rain, or the overflow of bath tubs or the like, since the bond or key thus provided for the set material is slight and easily broken, even when not subjected to accidental soaking of water. Moreover, the laths are frequently set too close together or too far apart, in both cases resulting in an ineffective key or bond to hold the set plastic material to the lathing. In wetting the laths, also, the character of the wood used, with its hard grain, prevents said laths from readily absorbing the water, causing said laths to buckle, making a bump in the wall, which by a sudden jar of the wall will cause the material to fall, which is frequently dangerous to the person or persons standing close by. By the use of my invention all of these deleterious results are effectively overcome.

It is accordingly an object of my invention to provide a novel form of lathing having means on the edges thereof, which may be in the form of grooves of any preferred shape or form, the outer edges of said grooves either overlapping each other or being flush, said grooves functioning to receive and hold the water so the laths may be thoroughly soaked, the face of said laths, if desired being also provided with indentations, grooves, in staggered relation, diagonally positioned

or otherwise, to receive the water, and later the plastic material, which, after it has set forms an effective key or bond to prevent the set material from cracking or falling, said laths, if desired being also provided with means whereby they may be secured in place on the building.

The above and further objects and advantages of my invention as will herein-after more fully appear, I attain by the construction described in the specification and illustrated on the drawing, forming a part of my application.

Reference is had to the accompanying drawing, in which similar reference characters denote similar parts. In the drawing,

Fig. 1 is a fragmentary front elevational view showing the laths in place, the plastic material being cut away to disclose same,

Fig. 2 is a cross-sectional view, taken on the line 2—2, Fig. 1, looking in the direction of the arrows,

Fig. 3 is a fragmentary side elevational view of a lath showing one form of indentations,

Fig. 4 is a cross-sectional view, taken on the line 4—4, Fig. 3, and

Fig. 5 is a view similar to Fig. 3, but illustrating a lath equipped with diagonal indentations.

Describing my invention more in detail, while I preferably employ wood to form my novel form of lath, it is clear that other material may be used, the wood being preferably sawed or cut to the regulation size, and provided with grooves, holes, and indentations, to hold the water a sufficient time to soak the lath, and to break the hard grains which cause practically all the buckling, and enables the set plastic material to make a perfect clinch or bond.

It is to be understood that the term "lath" as used in the specification and claim is of the standard type, such as used in practice, which is substantially from 32" to 48" long, $\frac{1}{4}$ " to $\frac{3}{8}$ " thick and 1" to $1\frac{1}{8}$ " in width.

As seen in the drawing, 2 incides a lath, preferably of wood, adapted to be secured to the studs 4 by nails or any other preferred

fastening means, said laths having cut-away or formed on the edges thereof grooves 6, which may be V-shaped in form, curved or of other shape.

5 In putting on lathing, the workmen frequently place them too close together or too far apart, with the result that no clinch at all is formed for the plastic material, or when spaced too far apart the material is too heavy 10 and drops off, moreover, even when properly spaced apart, the workmen do not apply sufficient force to form a key. By the use of my invention it is impossible not to form a proper key, irrespective of the character of 15 the labor of the workman.

As seen in the drawing, indentations or depressions may be formed in the lathing 2, on one or on both sides, said indentations being indicated by the reference numeral 14. Any 20 preferred arrangement of said indentations may be used, either diagonally, staggered or otherwise, so long as the grain is broken.

The character of the indentations, also, 25 may be varied, as well as their positions as in practice desired.

After the lathing has been secured in position, water is always sprayed thereon before the plastic material is applied, and the more water the laths absorb the better results will be obtained. When the wood has 30 hard grains running therethrough, it does not readily absorb the water. This feature is taken care of by the indentations, and after the wet plastic material is applied, the 35 hard grains slowly take up the water and cause the lathing to buckle, with the results herebefore described. When the lathing dries, it assumes its original position, and the plastic material drops off.

40 The indentations, as shown and described provide an effective means for insuring that the lathing be thoroughly soaked before the plastic material is applied. Moreover, there is a great saving of material in that every 45 indentation forms an effective key or clinch, and there is no dropping and consequent loss of material.

By the use of my invention heavy rains or 50 the overflow of sinks, bath tubs and the like have no effect upon the tight hold of the plastic material as just described. There is no breaking off of material forming a clinch back of the lathing.

55 While I have thus described my invention with great particularity, I do not propose to be limited to the exact details of construction shown and described, but reserve the right in practice to make any and all modifications thereof that fall within the scope 60 of the appended claims.

I claim as my invention:

1. A lath provided with sets of staggered shallow indentations to cut the grain of said lath, extending only part way into said lath 65 whereby said lath will be prevented from

buckling when associated with a building construction.

2. A lath provided with sets of shallow indentations on both sides thereof, which indentations are adapted to break the grain 70 of the material of said lath so that expansion and contraction thereof will be compensated for when plaster is applied to prevent said plaster from cracking or falling.

3. A lath provided on both sides thereof 75 with sets of shallow indentations of varying depth and positioned in said lath in such a manner that the grain in the material of said lath will be broken to compensate for expansion and contraction thereof so said lath may 80 be nailed to a building construction at any point thereof without weakening said lath.

In testimony whereof I have signed my name to this specification.

HARLOW H. HATHAWAY.
